IRONING SHOE

Arthur H. Happe, Detroit, Mich., assignor of one-half to Herman A. Sperlich, Detroit, Mich.

Application February 11, 1941, Serial No. 378,392

2 Claims. (Cl. 219—19)

The present invention relates to ironing shoes for ironing machines or the like and among the objects thereof is a shoe which is more efficient in heating and retains its heat for a longer period than those heretofore in use.

Another object is a heating element and mounting which retains its efficiency and does not become less efficient with age and use.

Still another object is a shoe in which the heating unit may readily be replaced if such operation should become necessary.

Another object is a shoe in which the heating is accomplished by radiation rather than is usually attempted by contact and direct absorption.

Other objects will readily occur to those skilled in the art upon reference to the accompanying drawings and the following specification.

In the drawings:

Figure 1 is a front view in elevation of a shoe.

Figure 2 is a back view in elevation of the same.

Figure 3 is a view similar to Figure 2 but with parts removed.

Figure 4 is a view of the inner face of the insulating pad.

Figure 5 is an end view of the shoe.

Figures 6 and 7 are respectively sections on the lines 6—6 and 7—7 of Figure 2.

As indicated, the shoe comprises a metal, preferably cast iron, casting 10 having its front face 11 suitably curved to cooperate with a roll (not shown) and having its rear face flattened and provided with a narrow, relatively deep groove 15 extending completely around the face near the edge thereof. Suitable screw studs 16 are also fixed in said face for securing in place the insulating pad indicated as a whole at 17.

The pad 17 consists of a sheet metal tray 17a level full of a suitable heat insulating material 17b, the preferred material being that described in my copending application, Serial No. 375,923, filed January 25, 1941, on Heat insulating material.

While this material is preferred, there may be used any suitable material having the characteristics of high heat insulating quality, high heat resistance, and more or less physical penetrability, i. e., sponginess and somewhat soft.

The heating element itself consists of a suitable coiled wire 20 upon which is strung a plurality of short pieces of high dielectric refractory tubes 21 of such dimension laterally as to fit loosely within the narrow relatively deep groove 15. The ends of the coil are connected to the terminal posts 22 carried in a high dielectric refractory block 23, the element 20—21 being placed in groove 15 and maintained in place by the pad 17. Suitable openings in the latter provide for passage of the studs 16 and the outer face of block 23.

In preparing the several parts before assembly, the grooves 15 are coated inside with a suitable coating material which is black in color and remains permanently so while the adjacent face 10 of the shoe is coated with aluminum paint. Further, the refractory tubes 21 may be coated with a similar black coating either inside or out or both.

Further the face of the material 17b adjacent the shoe 10 is likewise coated with aluminum paint before assembly.

It should also be noted that the grooves 15 may be cored grooves and, therefore, do not necessarily fit the tubes 21 so that a large area 15 of contact between the tubes and the groove walls does not usually exist and the heating of the shoe 10 is through radiation from the greater part of the perimeter of the heating element embedded in the groove, assisted by the black absorptive surface. The aluminum painted surfaces aid in maintaining the temperature of the shoe is preventing to a great extent the passage of heat to and into the mass of insulation.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. An ironing shoe consisting of a metal shoe having a groove in the rear face thereof, said groove having a permanently black coating on the walls thereof, an electric heating element seated loosely in said groove, said element consisting of a resistance heated wire passing through sections of porcelain tubing, a body of heat insulating material secured over said face and groove and retaining said element in the latter, means in said groove for aiding absorption of heat from said element and means for reducing absorption of heat from said shoe by said insulating material.

2. An ironing shoe consisting of a metal shoe having a groove in the rear face thereof, said groove having a permanently black coating on the walls thereof, an electric heating element seated loosely in said groove, said element consisting of a resistance heated wire passing through sections of porcelain tubing, each being provided with a permanently black coating on its inner and outer surfaces, a body of heat insulating material secured over said face and groove and retaining said element in the latter, means in said groove for aiding absorption of heat from said element and means for reducing absorption of heat from said shoe by said insulating material.
